UNITED STATES PATENT OFFICE.

WILLIAM BRADY, OF SAN FRANCISCO, CALIFORNIA.

ROCK-DRILL.

SPECIFICATION forming part of Letters Patent No. 769,465, dated September 6, 1904.

Application filed December 17, 1903. Serial No. 185,486. (No model.)

To all whom it may concern:

Be it known that I, WILLIAM BRADY, a citizen of the United States, residing in the city and county of San Francisco and State of California, have invented new and useful Improvements in Rock-Drills, of which the following is a specification.

My invention relates to improvements in apparatus which is designed for striking blows in rapid succession, as in drilling rock, operating hammers or stamps, or for any like purposes.

It consists in the combination, with the part to be impelled, of cylinders fixed in line with each other having a piston - rod common to both connected with the impelled part and pistons fixed to the piston-rod within each cylinder. A forward impulse is given to these pistons alternately by a suitable medium under pressure and means are provided for returning the implement and pistons after the stroke has been completed by the momentum of the apparatus as transmitted through suitable fly-wheels carried thereby.

Referring to the accompanying drawings, Figure 1 is a plan view of drill, showing my invention. Fig. 2 is a portion of same, showing modification.

As shown in the accompanying drawings, A and B are two cylinders connected together and in line with each other, having an intermediate space between them. These cylinders have pistons reciprocable within them, a piston-rod common to both and extending outwardly through one of the cylinder-heads and connected with a head, as at 2, this head being adapted to carry a drill or other device, as at 3, for striking blows.

As shown in my present invention, the pistons are designed to be impelled by an explosive vapor, such as that of gasoline, and suitable valves, as at 4, are provided for the admission of the explosive mixture at the proper intervals. Exhaust-passages 5 are properly located to allow the expulsion of the products of explosion after the stroke has been completed, and any suitable or well-known devices may be employed for igniting the charges when compressed after the cylinders have been filled in the manner well known for this

class of engines, this being not further explained, as it is no part of my present invention.

A shaft 6 is journaled across the apparatus. 9 is a sprocket-wheel fixed upon the end of 55 the shaft 6, and an endless chain 10 passing around this sprocket - wheel extends rearwardly and passes around another sprocket-wheel, 11, fixed upon a shaft 12, which is suitably journaled across the machine, as shown. The sprocket 11 is half the size of sprocket 9, so that through connections hereinafter described the proper movement of the exhaust-valves and other parts will be effected. Upon this shaft 12 are fly - wheels, as shown 6: at 13. These fly - wheels have a sufficient weight to continue by their momentum the movement of the parts, so that after having received an impulse by which they are set in motion, they will continue to move while the 7c pistons are returning for another stroke.

14 represents crank - pins fixed to the fly-wheels or connected with the shaft.

15 represents rods extending forwardly and having their front ends connected with a cross-bar 16. This cross-bar is slidably upon the drill shank or carrier and in front of the drill head or chuck 2, and the movements of the parts are so timed that the cross-head will be forced forward with the revolution of the shaft 12 and 8c wheels 13, so that at the instant of the explosive action upon the pistons, by which the drill or equivalent striking apparatus is impelled forward, the cross - bar will be moved to its farthest forward position, thus allowing the 85 drill to be moved and to strike its blow with full force. The momentum of the fly-wheels 13, connected through the rods 15 upon the cross-bar 16, will draw it back, sliding upon the drill-shank until it contacts with the 90 cushion 17 upon the front end of the drill head or chuck 2, and this acts to force the drill - head, connecting parts, and the pistons in the cylinders back to the rear ends, thus first expelling the gases resulting from 95 the previously-exploded charge in one cylinder and charging the other cylinder in readiness for explosion. The cushion 17 relieves the shock of the returning cross-bar when it strikes the drill-head. By this means the re- 100

turn movement of the drill, which would otherwise have to be provided for by some independent mechanism, is made automatic, and the slidability and independent movement 5 of the cross-head 16 with relation to the parts impelled by the pistons provides for a sufficient movement to the drill or its equivalent and the return of the drill to be afterward effected by the contact of the cross-bar with 10 the drill-head, as previously described.

The igniters and exhaust-valves 4 and 5 are actuated as follows: A disk 7 is fixed on the shaft 6, and this disk has a crank-pin 21 and connecting-rod 20, extending back substantially parallel with the cylinders. This rod is reciprocated by the crank-pin, and it carries contact bars or lifters 23, which engage with arms 24, projecting from the exhaust-valve stems, so that they will be engaged by 15 these lifters 23 to alternately actuate the valves in proper relation with the movements of the pistons.

It will be understood that the proportion of the sprockets 9 and 11 with relation to each 25 other will be such as to properly time the movements of the exhaust-valves and the ignition devices with reference to the reciprocations of the pistons. The inlet-valves may be opened by suction.

30 If a fly-wheel is fixed upon the shaft 6, as shown in my former patent, No. 740,800, dated October 6, 1903, the second shaft 12 and the connecting-rods 15 may be omitted and the crank 14^a transferred to the shaft 6. The connection 35 between the crank and the drill-head may be made in this case by means of a loose chain 15^a, extending from a loose sleeve on the crank to a fixed connection on the drill-head. The revolution of the crank slackens 40 the chain at the instant the drill strikes the rock and allows the drill to impart its blow, and the momentum of the fly-wheel returns the crank and through the chain draws the drill back and returns the parts, as previously 45 described.

Having thus described my invention, what I claim, and desire to secure by Letters Patent, is—

1. The combination in an apparatus for 50 striking blows, of cylinders fixed axially in line, pistons movable in the cylinders having a piston-rod common to both and extending through the end of one of the cylinders, a tool-carrying head fixed to the piston-rod, a device for returning the parts after each 55 stroke, said device having one end adapted to reciprocate in line with the tool-head, a journal-shaft having cranks with which the rear end of said device is connected, a fly-wheel 60 carried by said shaft, and receiving motion from the impulses of the engine, the momentum of said fly-wheel acting through the crank-shaft connections to retract the drill and pistons after the latter has been impelled 65 forward.

2. A reciprocating apparatus consisting of cylinders in line with each other having pistons movable in each, a piston-rod common to both, and a drill or like head with which the piston-rod connects, inlet and exhaust valves 70 connected with the rear of the cylinders, a mechanism by which the pistons are automatically moved to the rear of the cylinders to alternately compress an explosive charge and to expel residual products, said mechanism consisting of parallel journaled shafts transverse to the cylinders, fly-wheels fixed upon one of said shafts, sprocket-wheels upon both shafts and an endless chain connecting them, and mechanism whereby the second shaft is rotated, said 75 mechanism consisting of cranks connected and movable with a cross-head slidable with relation to the drill and its head.

3. The combination in a rock-drill of a plurality of power-cylinders having pistons movable therein, a drill-head with which the pistons are connected, a drill carried by said head and movable in unison therewith, mechanism by which the parts are returned after a stroke has been delivered, said mechanism consisting 80 of a cross-head connected and reciprocable in line with the drill, parallel shafts journaled transverse to the cylinders, said shafts having sprocket-wheels, an endless connecting-chain, fly-wheels mounted upon one of the shafts, 85 cranks, and connecting-rods extending from the cranks to the cross-head, and a cushion interposed between the cross-head and the drill-head against which the cross-head contacts 90 upon its return movement.

4. The combination with a rock-drill and mechanism connected therewith whereby the drill is impelled and a blow given by an explosion at the rear thereof, of means for automatically returning the drill after the explosion, said means consisting of a cross-head slidable upon the drill-shank, a cushion interposed between said cross-head and the drill-head against which said cross-head impinges upon its return movement and by which it retracts the drill and its actuating mechanism, a shaft having fly-wheels and cranks, and connecting-rods between said cranks and the ends of the cross-head, a second shaft parallel with the first-named shaft, sprocket-wheels upon 105 both shafts and an endless chain whereby motion is transmitted between the two, a crank mounted upon the second shaft, and connections between said crank and the exhaust-valves whereby motion is transmitted between 110 said reciprocating and revoluble parts.

5. The combination in a rock-drill of a plurality of cylinders axially in line, having pistons and a piston-rod connected with both pistons and with a drill-carrying head exterior 125 to one of the cylinders, inlet and exhaust valves to each of said cylinders, a rod having toes or lifters engaging corresponding arms upon the exhaust-valve stems, a shaft journaled transversely to the engine-cylinders, 130

said shaft carrying a fly-wheel, a crank with which the valve-actuating rod is connected, a crank upon the fly-wheel shaft, and connection between said crank and a cross-head, whereby the momentum of the fly-wheels is transmitted to advance the cross-head to allow a free movement of the drill under the explosive action within the cylinders, and a cushion upon the drill-head against which the cross-head impinges and by which the drill and re-

ciprocating pistons are automatically retracted.

In testimony whereof I have hereunto set my hand in presence of two subscribing witnesses.

WILLIAM BRADY.
